UNITED STATES PATENT OFFICE

2,133,554

HINGE

John Ludwig, Detroit, Mich.

Application January 28, 1937, Serial No. 122,735

7 Claims. (Cl. 16—148)

My invention relates to a new and useful improvement in a hinge and particularly a hinge of the concealed type.

It is an object of the present invention to provide a hinge of this type which will be simple in structure, economical of manufacture, durable in use, easily and quickly installed, and one which will not affect the appearance or mar the beauty of the body on which mounted.

Another object of the invention is the provision of a concealed hinge on which a swinging body may be mounted and which will carry the maximum load and afford the desired strength in a hinge of this class.

Another object of the present invention is the provision of a hinge of this type, so constructed and arranged that it will serve, in itself, to form a check on the swinging movement of the body to open position.

Another object of the invention is the provision of a hinge so constructed that it may be reversed for use either as a right hand or a left hand hinge and which will accommodate itself to a curved body, such as a stream-lined vehicle body.

Other objects will appear hereinafter.

The invention will be best understood from a reference to the accompanying drawing which forms a part of this specification and in which,

Fig. 1 is a central sectional view of the invention showing it applied,

Fig. 2 is an end elevational view of the invention with parts broken away and parts shown in section, said view being taken substantially on line 2—2 of Fig. 1,

Fig. 3 is a fragmentary view taken on line 3—3 of Fig. 2,

Fig. 4 is a view taken on line 4—4 of Fig. 1,

Fig. 5 is a sectional view taken on line 5—5 of Fig. 1,

Fig. 6 is a fragmentary end elevational view of the invention.

The invention is intended for use in mounting a swingable body 11 on a stationary support 12. Particularly on the stream-lined automobile bodies, it is desirable to remove all outward projections. The present invention provides a hinge which may be used in mounting a vehicle door on the vehicle body and the hinge itself may be concealed. The hinge comprises a pair of main sections or butts, one of which is U-shaped and embodies the legs 13 and 14 connected by the bight 15. Each of these legs is provided at its end with the angularly turned lugs 16 having the rounded corners 17. This U-shaped body is the

stationary part of the hinge and is housed in a cavity or recess 15' formed in the body 12, the angularly turned portions or lugs 16 being secured to the body by means of bolts 17.

The other main portion or butt of the hinge 15 comprises an L-shaped portion, the base 20 of which is slightly inclined outwardly from the leg 19 and formed shorter than the leg 19. An angularly turned portion 21 is formed integral with the base 20 and formed into a knuckle 22 at the juncture of the portion 21 with the base 20 and also formed into a knuckle 23 at its end. The leg 19 is secured by the bolts 24 or in any other suitable manner to the swingable body or door 11.

A pintle 25 extends through the legs 13 and 14 as shown in Fig. 5. This pintle passes through a spacing sleeve 26 and also through one end of the short connecting links 27 and 28. The sleeve 26 is of such length and the links 27 and 28 are 20 of such thickness that when these parts are assembled as shown in Fig. 5 they are snugly engaged between the legs 13 and 14.

A pintle 29 extends through the legs 13 and 14 and through one end of the longer links 30 and 31. This pintle also extends through the coils of a spring 32. These coils are formed from a single piece of wire, the center portion of which is doubled upon itself to provide a tongue 33 and the ends 34 and 35 of which are angularly 30 turned so as to, when the hinge is swung open a predetermined distance, engage with the faces of the links 30 and 31 which are directed away from the bight 15. The base 20 is formed of a width corresponding with the length of the sleeve 35 26 and the links 27 and 28 are formed of the same thickness as are the links 30 and 31. The links 27 and 28 overlie the knuckle 22 and a pintle 36 is passed through the knuckle 22 and the ends of the links 27 and 28 so that the portion of the hinge which is connected to the door 11 is pivotally mounted on the pintle 36. The knuckle 23 lies between the ends of the links 31 and 30 and a pintle 37 is passed through these links and through the knuckle 23. This pintle 40 37, it will be noted, does not extend through the legs 13 and 14 but is of a length to snugly fit between the same.

As shown in Fig. 5, the angularly turned ends 34 and 35 are not in engagement with the links 50 30 and 31 when the door is in closed position. However, as the door swings outwardly as shown in the dotted line illustration in Fig. 1, the links 30 and 31 swing on the pintle 29 and engage the angularly turned ends 34 and 35 of the spring. 55

Further outward swinging toward the open position of the door will effect a further swinging of the links 30 and 31 which would have a tendency to wind the coils 32 of the spring. Consequently, this spring functions to check the outwardly or opening swinging movement of the door after the door has swung toward open position a predetermined distance. The spring therefore serves as a check for resisting open swinging of the door after the door has swung open a predetermined distance and therefore the check straps which are commonly used on vehicle doors may be eliminated. When the door swings to its fully open position the stop shoulder 46 will engage the knuckle 26. This engagement however, will be an "easy" engagement because of the resistance offered by the spring.

When the door is swung to shut position, the space between the legs 13 and 14 will, of course, not be visible, but when the door is swung to open position, this space would be visible and would seriously affect the appearance of the body on which mounted. In this invention, I have provided means for closing the space between the legs 14 and 13 when the door is swung to open position. This is accomplished by means of a plate 40 which has, at one end, the lateral extensions or wings 41, which overlie and are adapted to engage one face of the legs 13 and 14. The opposite end of the plate 40 is provided with the inwardly turned tongues 42 and 43, which are crimped around the leg 19 of the hinge section, so that this plate is slidable on the leg 19. As the door is swung to open position, the wings 41 riding on the legs 13 and 14 will slide the plate rearwardly on the leg 19, so that when the door is swung to fully open position, the plate 40 will serve as a closure for the space between the legs 13 and 14. As the door is swung to closed position, the end of the plate 40 will engage the base 15 of the cavity or recess in the body 12 and the plate will be slid into the position shown in full lines in Fig. 1.

While I have illustrated and described the preferred form of construction, I do not wish to limit myself to the precise details of structure shown but desire to avail myself of such variations and modifications as come within the scope of the appended claims.

Having thus described my invention, what I claim as new and desire to secure by Letters Patent is:

1. A hinge of the class described, adapted for mounting a swingable body on a stationary body comprising a pair of hinge butts, one of said butts being adapted for attachment to one of said bodies and the other of said butts being adapted for attachment to the other of said bodies, one of said butts having a pair of spaced apart members; an angularly turned portion on the other of said butts and provided with a terminal angular portion, said terminal portion having a pair of spaced knuckles formed therein, a pair of links each having openings formed at opposite ends; a pintle for pivotally connecting one of the ends of said links to said spaced apart members and lying between the same, said links at their opposite ends overlying said terminal angular portion; a pintle projecting through said opposite ends of said links and through the inner knuckle in said angular terminal portion, said pintle lying between said spaced apart members and engaging the same in a snug fit; a pair of shorter links; a pintle projecting through one end of each of said shorter links and through the inner knuckle in said angular terminal portion, said pintle lying between said spaced apart members and engaging the same in a snug fit; a pair of spaced apart members for pivotally mounting one of the ends of said links on said spaced apart members; a spacing member on said pintle between said links, the opposite ends of said links overlying said terminal angular portion, and a pintle projected through said opposite ends of said shorter links and through the other knuckle of said terminal angular portion, said last-named pintle lying between said spaced apart members.

2. A hinge of the class described, adapted for mounting a swingable body on a stationary body comprising a pair of hinge butts, one of said butts being adapted for attachment to one of said bodies and the other of said butts being adapted for attachment to the other of said bodies, one of said butts having a pair of spaced apart members; an angularly turned portion on the other of said butts and provided with a terminal angular portion, said terminal portion having a pair of spaced knuckles formed therein; a pair of links each having openings formed at opposite ends; a pintle for pivotally connecting one of the ends of said links to said spaced apart members and lying between the same, said links at their opposite ends overlying said terminal angular portion; a pintle projecting through said opposite ends of said links and through the inner knuckle in said angular terminal portion, said pintle lying between said spaced apart members and engaging the same in a snug fit; a pair of shorter links; a pintle projecting through one end of each of said shorter links and through the inner knuckle in said angular terminal portion, said pintle lying between said spaced apart members and engaging the same in a snug fit; a pair of spaced apart members for pivotally mounting one of the ends of said links on said spaced apart members; a spacing member on said pintle between said links, the opposite ends of said links overlying said terminal angular portion, and a pintle projected through said opposite ends of said shorter links and through the other knuckle of said terminal angular portion, said last-named pintle lying between said spaced apart members.

3. A hinge of the class described, adapted for mounting a swingable body on a stationary body comprising a pair of hinge butts, one of said butts being adapted for attachment to one of said bodies and the other of said butts being adapted for attachment to the other of said bodies, one of said butts having a pair of spaced apart members; an angularly turned portion on the other of said butts and provided with a terminal angular portion, said terminal portion having a pair of spaced knuckles formed therein; a pair of links each having openings formed at opposite ends; a pintle for pivotally connecting one of the ends of said links to said spaced apart members and lying between the same, said links at their opposite ends overlying said terminal angular portion; a pintle projecting through said opposite ends of said links and through the inner knuckle in said angular terminal portion, said pintle lying between said spaced apart members and engaging the same in a snug fit; a pair of shorter links; a pintle projecting through one end of each of said shorter links and through the inner knuckle in said angular terminal portion, said pintle lying between said spaced apart members and engaging the same in a snug fit; a pair of spaced apart members for pivotally mounting one of the ends of said links on said spaced apart members; a spacing member on said pintle between said links, the opposite ends of said links overlying said terminal angular portion; a pintle projected through said opposite ends of said shorter links and through the other knuckle of said terminal angular portion, said last-named pintle lying between said spaced apart members; and yieldable means mounted on said first-named pintle for yieldably resisting movement of said butts relatively to each other in one direction beyond a predetermined distance.

4. In a hinge of the class described, a pair of sections; means for mounting said sections on each other in swingable relation, one of said sections having a pair of spaced apart members between which and outwardly from which the other of said sections swings; and a closure blade slidably mounted on said other section and adapted upon swinging of said other section into a predetermined position relatively to said section having said spaced apart members, for closing the outer end of the space between said members.

5. In a hinge of the class described, a pair of hinge butts; means for mounting said butts on each other in swingable relation, one of said butts having a pair of spaced apart members between which and outwardly from which the other of said butts swings; and a closure plate movably mounted on said other butt and adapted upon swinging of said other butt to a predetermined position relatively to the butt having said spaced apart members for closing the outer end of the space between said members.

6. In a hinge of the class described, a pair of hinge butts; means for mounting said butts on each other in swingable relation, one of said butts having a pair of spaced apart members between which and outwardly from which the other of said butts swings; and a closure plate movably associated with said other butt and adapted, upon

swinging of said other butt into a predetermined position relatively to said butt having said spaced apart members, for movement into position for closing the outer end of the space between said 5 members; and means cooperating with said plate for effecting movement of said plate to closing position upon swinging of said other butt into said predetermined position.

6. A hinge of the class described, comprising: 10 a pair of hinge butts; an angularly turned portion on one of said hinge butts, said angularly turned portion having a knuckle formed therein; a laterally offset portion on said butt and terminating in a knuckle; two sets of links; 15 a pair of pintles, each of said sets of links being pivotally mounted at one of their ends by a pintle on the other of said butts; a pintle for pivotally connecting the free ends of one of said sets of links to one of said knuckles; a pintle for pivotally connecting the other of said links to the other of said knuckles; and a spring 20 mounted on one of said pintles and adapted upon relative swinging of said butts in one direction

a predetermined distance for engaging one of said sets of links for yieldably resisting further relative swinging movement of said butts in said direction.

7. A hinge of the class described, comprising: 5 a pair of hinge butts; an angularly turned portion on one of said hinge butts, said angularly turned portion having a knuckle formed therein; a laterally offset portion on said butt and terminating in a knuckle; two sets of links; 10 a pair of pintles, each of said sets of links being pivotally mounted at one of their ends by a pintle on the other of said butts; a pintle for pivotally connecting the free ends of one of said sets of links to one of said knuckles; a pintle for pivotally connecting the other of said links to the other of said knuckles; and yieldable means 15 adapted upon relative swinging of said butts in one direction a predetermined distance for yieldably resisting further swinging movement of said 20 butts in the same direction.

JOHN LUDWIG.
